UNITED STATES PATENT OFFICE

EARL R. PHARES, OF AUDUBON, IOWA

CAP STRETCHING AND RESHAPING IMPLEMENT

Application filed March 2, 1932. Serial No. 596,317.

This invention relates to an expandable and contractible device or implement expressly constructed and designed for stretching and reshaping damaged caps such as worn by men and boys.

The invention is similar in some respects to tools and devices used in hat pressing and cleaning establishments for blocking and reconditioning soiled and damaged hats, but is specifically fashioned and designed to adapt it for reshaping caps such as have become mis-shapen from rain and dampness.

The purpose of the invention is to provide a device which is structurally different from known devices employed for the same purpose, whereby to provide a novel and practical accessory for this specific purpose which is efficient in performance, positive and dependable in action, and an appreciable achievement in this line of endeavor.

In the accompanying drawings illustrative of the preferred structural embodiment of the invention:

Figure 1 is an elevational view of a device constructed in accordance with the present invention.

Figure 2 is a top plan view thereof.

Figure 3 is a view like Figure 2 showing the device expanded.

Figure 4 is a section taken approximately on the plane of the line 4—4 of Figure 2.

Figures 5 and 6 are perspective views of the superposed companion disc-like plates.

Figure 7 is a detail section on the line 35 7—7 of Figure 4.

Figure 8 is a detail perspective view.

Figure 9 is a detail section on the line 9—9 of Figure 3.

The general assembly of the invention is evident from a contrast of Figures 1 and 4 and referring to these figures it will be seen that the numeral 10 designates the relatively stationary plate, this being in the form of a disc having a marginal groove 11 and circumferentially spaced notches 12. The cen-

ter of the plate is apertured as at 13 to accommodate the smooth end portion 14 of a feed screw 15. Washers 16 are keyed or otherwise rigidly fastened to the shaft above and below the plate so as to form a swivel connection of the shaft with the plate.

The notches 12 serve as keeper seats and are spanned by a wire ring 17 which is seated in the groove 11. The relatively movable disc or plate is distinguished by the numeral 18 and is somewhat smaller in diameter than the first plate but has similar characteristics. For example, the marginal portion is provided with circumferentially spaced notches 19 and a marginal groove 20 receiving a wire ring 21. The ring here serves as a pivotal mounting for the hinge eyes 22 on the upper ends of the flat metal arms 23 of the expandable and contractible unit 24.

The lower end of each arm is provided with an arcuate plate or form 25 of appropriate shape occupying the approximate angularity illustrated in Figure 9. This form is concealed in a felt or suitable fabric protector 26. The last-named ends of the arms 23 extend through the notches 12 and are confined therein by the embracing ring 17. The screw-threaded portion of the shaft or screw 15 is threaded through a collar 27 secured in a central opening in the disc 18.

On the upper end of the feed screw is a handwheel 28 shaped for convenient manipulation. The numeral 29 merely designates a washer as shown in Figure 7.

The gist of the invention is in the provision of the notched plate or disc 10 having the feed screw 15 concentrically and swivelly connected thereto, together with a superposed smaller disc having the screw-threaded collar through which the threaded portion of the feed screw is adjustable. The plate or disc thus arranged serve to accommodate the units 24 which are hingedly connected to the upper disc 18 and are longitudinally slidable

through the notches 12 in the relatively stationary disc 10.

The cloth covered forms are located below the plate 10 and, collectively considered, they are disposed, when in contracted position, in the overlapped state represented in Figure 2. It is evident therefore that the turning of the feed screw through the medium of the hand-wheel 28 serves to adjust the disc 18 up or down according to the direction of rotation, on the shaft 15. Hence the unit 24 may be expanded or contracted to accommodate different sized caps.

The covered form on the ends of the arms 15 of the units 24 co-operate in forming an expandible and contractible annulus which may be placed in the cap band to stretch the cap and convert it from a distorted elongated shape to its original circular shape. Thus, 20 with the use of this device and a suitable steam buck such as are used in cleaning establishments, it is possible to subject the cap to momentary action of the steam, and by a proper method of pressing to reblock the cap, 25 so to speak, and provide it with its original uniform shape.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming 35 within the field of invention claimed may be resorted to if desired.

I claim:

1. A cap reshaping device comprising a relatively stationary disc-like plate, a feed screw concentrically and swivelly connected to and rising from said plate and having operating means on its upper end, a somewhat smaller disc-like plate mounted for adjustment on said feed screw and movable toward and from said first-named plate, a plurality of companion expandible and contractible units provided at their lower ends with overlapping complementary form sections, the upper ends of the units being hingedly attached to said second-named plate and the intermediate portions thereof being slidably associated with the marginal portion of the first-named plate.

2. A cap reshaping device of the class described comprising a relatively stationary disc having marginal keeper notches and a marginal groove, a ring seated in said groove and spanning the notches, a feed screw 60 swivelly connected to the central portion of said disc, a relatively movable disc smaller than the first-named disc and threaded on said feed screw and having marginal notches and a peripheral groove, an operating handle 65 on the upper end of the feed screw above said

second-named disc, a plurality of expander units arranged in circumferentially spaced order with respect to the discs, each unit comprising an arm having an eye at its upper end pivoted on the second-named ring and movable in the adjacent notch, the intermediate portion of the arm extending down through the aligned companion notch on the first-named disc and terminating in an arcuate member forming one of the sections on an annulus.

In testimony whereof I affix my signature.

EARL R. PHARES.
